UNITED STATES PATENT OFFICE.

GEORGE PILSON, OF YONKERS, NEW YORK.

SAFETY-DOG FOR ELEVATORS.

SPECIFICATION forming part of Letters Patent No. 278,595, dated May 29, 1883.

Application filed April 14, 1883. (No model.)

To all whom it may concern:

Be it known that I, GEORGE PILSON, of Yonkers, in the county of Westchester and State of New York, have invented a new and Improved Safety-Dog for Elevators, of which the following is a full, clear, and exact description.

The object of my invention is to provide a new and improved device for holding an elevator-car in place if the cable breaks, and thus prevent the car from being dashed against the bottom of the shaft.

The invention consists in sliding dogs provided with threaded apertures, into which the threaded ends of a shaft in the car pass, which shaft is surrounded by a coiled spring, which is released by means of a cord passing around the cable-drums with the cable when the cable breaks, whereby the said spring will uncoil and revolve the shaft, thereby moving the dogs or blocks outward from the sides of the car, and causing them to engage with the teeth of vertical racks in the elevator-well.

Reference is to be had to the accompanying drawings, forming part of this specification, in which similar letters of reference indicate corresponding parts in both the figures.

Figure 1 is a longitudinal sectional elevation of an elevator-car provided with my improvement. Fig. 2 is a detail cross-sectional elevation on the line $x x$, Fig. 1.

A shaft, A, is journaled in hangers B on the ceiling or top of the frame of an elevator-car, C, and to the said shaft one end of a spiral spring, D, is fastened, which spring is coiled around the shaft, and has its other end secured to a casing, E, surrounding the spring, which casing is held to a rod or bracket, F, projecting from the ceiling or top of the car. On the shaft A a ratchet-wheel, G, is rigidly mounted, adjoining the casing E, with which ratchet-wheel a pawl, H, engages, which is pivoted to the casing E. The shaft A is provided with one or more collars, J, having apertures a , for introducing rods or keys for rotating the shaft A to coil the spring D; or the shaft can be provided with any other suitable devices for applying a key for turning the shaft. The ends of the shaft A are provided with opposite screw-threads, and screwed

into apertures in the inner ends of sliding dogs or blocks K, having their outerends beveled downward, which dogs are adapted to slide outward from the sides of the car and to engage with vertical racks L, secured on the sides of the shaft. A cord, M, attached to the pawl H, passes over the pulley with the main cable N, and is wound and unwound with the same; or the cord M can pass through suitable eyelets or guides in the car, so that it can be pulled by persons in the car.

The operation is as follows: By turning the shaft A to wind up the spring D, the threaded ends of the shaft A are screwed into the threaded apertures in the blocks or dogs K, whereby the said blocks will be drawn inward and will be held in the position shown in Fig. 1. If the cable N breaks, the cord M will pull the pawl H upward, thereby releasing the spring D, which immediately uncoils, thereby rotating the shaft A in such a manner that the threaded ends of the same are screwed out of the blocks or dogs K, whereby the said dogs will be forced outward and between the teeth of the racks L, with which they engage, thereby holding the elevator-car in place and preventing it from dropping. The dogs cannot slip over the edges of the teeth of the rack L, as the shaft A holds them in place. As stated, the cord M can be so arranged that it can be pulled by a person in the car in case the descent of the car is to be stopped.

Having thus described my invention, what I claim as new, and desire to secure by Letters Patent, is—

1. The combination, with an elevator-car, of laterally-sliding dogs, and a shaft provided with opposite screw-threads at the ends for operating the said dogs, substantially as herein shown and described, and for the purpose set forth.

2. The combination, with an elevator-car, of laterally-sliding dogs, a shaft provided with opposite screw-threads engaging with screw-threads on the dogs, and of a spring for revolving the said shaft to throw the dogs outward, substantially as herein shown and described, and for the purpose set forth.

3. The combination, with an elevator-car, of the sliding dogs K, the shaft A, having oppo-

site screw-threaded ends, the spring D, the casing E, the ratchet-wheel G, and the pawl H, substantially as herein shown and described, and for the purpose set forth.

5 4. The combination, with an elevator-car, of the sliding dogs K, the shaft A, having opposite screw-threaded ends, the spring D, the casing E, the ratchet-wheel G, the pawl H,

and the collars J, for turning the shaft to coil the spring D, substantially as herein shown to and described, and for the purpose set forth.

GEORGE PILSON.
